UNITED STATES PATENT OFFICE.

MATTHEW H. SLOAN, OF CUMBERLAND, MARYLAND, ASSIGNOR TO THE WELLINGTON
GLASS COMPANY, OF CUMBERLAND, MARYLAND, A CORPORATION OF MARYLAND.

DESIGN FOR A LAMP-SHADE.

44,115.

Specification for Design.

Patented May 27, 1913.

Application filed April 10, 1913. Serial No. 760,319. Term of patent 14 years.

To all whom it may concern:

Be it known that I, MATTHEW H. SLOAN, a citizen of the United States, and residing at Cumberland, in the county of Allegany and State of Maryland, have invented a certain new, original, and ornamental Design for a Lamp-Shade, shown in the accompanying drawings, Figure 1 being a side elevation thereof, and Fig. 2 a view in top plan.

I claim:—

The ornamental design for a lamp shade, as shown.

MATTHEW H. SLOAN.
